UNITED STATES PATENT OFFICE.

WILLIAM H. COLLIER, OF SANDUSKY, OHIO.

CARBURETOR.

1,426,714.

Specification of Letters Patent. Patented Aug. 22, 1922.

Application filed June 7, 1917. Serial No. 173,303.

To all whom it may concern:

Be it known that I, WILLIAM H. COLLIER, a citizen of the United States of America, and a resident of Sandusky, Erie County, 5 State of Ohio, have invented Improvements in Carburetors, of which the following is a specification.

My invention relates to improvements in carburetors, and comprises improved means 10 whereby a very thorough mixture of air with the liquid or atomized fuel may be obtained; also other features, as hereinafter described and particularly pointed out in the appended claims.

15 The object of my invention is to produce a simple and inexpensive carburetor, which shall be highly efficient, shall produce a very thorough, intimate, and uniform mixture of fuel and air, and shall be compact and free 20 from liability to derangement.

I will now proceed to describe my invention with reference to the accompanying drawing, in which a carburetor embodying my invention is illustrated, and will then 25 point out the novel features in claims.

In said drawings:

Figure 1 shows a central vertical section of my improved carburetor, and Figure 2 shows a horizontal section thereof on the 30 line 2—2 of Figure 1.

My improved carburetor, in the form shown, comprises a top member 1, having secured to it a bowl member 2 provided with a central tubular portion 3, having the form 35 of a Venturi tube, and secured to the top member 1; the bore 4 of this top member 1 constituting a continuation of the Venturi tube, and containing the usual butterfly throttle valve 5. Within the bowl of the 40 carburetor is the usual float 6, controlling an inlet valve 7, illustrated diagrammatically.

Air is admitted to this central mixing chamber (Venturi tube) through a plurality 45 of lateral passages, 9, arranged tangentially, as shown particularly in Figure 2. Whereby a whirling motion is imparted to the air entering said mixing chamber; a motion which conduces greatly toward the formation 50 of a thorough mixture with the fuel entering said mixing chamber, as described presently.

For the admission of fuel to the mixing chamber said chamber is provided with a 55 central nozzle 10, the bore of which communicates, through a lateral duct 11, and a

vertical passage 12, with the interior of the carburetor bowl. A drain cock 13 is also provided, which communicates with the lateral duct 11. 60

For idling and similar low-speed light-work operation, a separate nozzle is provided, consisting of a duct 14, bored through top member 1 at or near the closed position of the throttle valve, and extended by a 65 small-bore tube 15 to near the bottom of the bowl; and this duct 14 also communicates with the upper portion of the carburetor bowl, at a point well above the normal level 70 of the liquid therein. At very slow speed, 75 with the throttle valve slightly open, the suction of the engine will draw fuel up through the tube 15, and air or vapor from the upper portion of the bowl, the mixture discharging through the duct 14 into the space beyond the throttle valve.

It will be obvious that owing to the whirling motion given to the air entering through the tangential passages 9, which whirling air currents circulate around the nozzle 10 80 and in so doing mix with each other and with the fuel jet projected from said nozzle, a very thorough mixture of the air with the fuel is produced.

This application involves, in part, features 85 disclosed, described, and claimed in my companion application, Serial No. 173301, filed of even date herewith.

What I claim is:

1. A carburetor comprising a member provided with a normally vertical mixing passage, having its walls contracted at an intermediate point to form a Venturi throat, a plurality of lateral air inlet passages leading tangentially into the lower part of said mixing passage, and a fuel jet nozzle centrally disposed within said mixing passage and projecting upwardly into said Venturi throat portion. 90

2. In a carburetor, a bowl member having 100 a central mixing passage and a surrounding annular fuel space, and having beneath that fuel space a plurality of lateral air inlet passages leading from the outside to said central mixing passage and arranged substantially tangentially with respect to said mixing passage, and a nozzle centrally disposed within said mixing passage and connected to said fuel space. 105

3. In a carburetor, a bowl member having 110 a central mixing passage and a surrounding annular fuel space, and having

beneath that fuel space a plurality of lateral air inlet passages leading from the outside to said central mixing passage and arranged substantially tangentially with respect to 5 said mixing passage, a nozzle centrally disposed within said mixing passage and projecting up thereinto from the bottom of the bowl member, and a duct connecting said nozzle with said fuel space and passing 10 through the bottom of the bowl member and

through one of the walls between said inlet passages.

In testimony whereof I have signed this specification in the presence of two subscribing witnesses.

WILLIAM H. COLLIER.
